UNITED STATES PATENT OFFICE.

GEORGE ELMER HEATON, OF THREE RIVERS, MICHIGAN.

RAILROAD-VELOCIPED AND DRIVING MECHANISM.

SPECIFICATION forming part of Letters Patent No. 601,439, dated March 29, 1898.

Application filed February 8, 1897. Serial No. 622,388. (No model.)

To all whom it may concern:

Be it known that I, GEORGE ELMER HEATON, a citizen of the United States, residing at the city of Three Rivers, in the county of 5 Kalamazoo and State of Michigan, have invented certain new and useful Improvements in Railroad-Velocipedes and Driving Mechanism, of which the following is a specification.

10 My invention relates to improvements in railroad-velocipedes and in propelling devices therefor.

The objects of my invention are, first, to provide a construction of railroad-velocipede 15 simple in construction; second, to provide a railroad-velocipede that can be run at a high rate of speed with small effort; third, to provide a railroad-velocipede of very light weight which is capable of practical use; fourth, to 20 provide a simple and improved propelling device specially adapted for use on railroad-velocipedes; fifth, to provide a construction of railroad-velocipedes which permits a great 25 variation of movement on the part of the operator in propelling the same. Further objects appear definitely in the detailed description. I accomplish these objects of my invention by the mechanism described in the following specification and illustrated in the 30 accompanying drawings, in which—

Figure 1 is a side elevation of the main portion of the machine, the arm H being shown in cross-section. Fig. 2 is a top plan view of the same, the arm being shown in dotted lines 35 in the folded position to indicate the manner of folding the same. Fig. 3 is a perspective view of the frame of the machine. Fig. 4 is an enlarged detail sectional view on line 4 4 of Fig. 3. Fig. 5 is an enlarged detail 40 perspective view showing the ratchet-pawl-propelling mechanism, taken in section on line 5 5 of Fig. 6. Fig. 6 is an enlarged detail view, being a plan of the ratchet-pawl and its mechanism shown in Fig. 5. Fig. 7 is a 45 sectional view on a line corresponding to line 5 5 of Fig. 6, showing a modified construction of a pawl for engaging the chain between the links.

In the drawings similar letters of reference 50 refer to similar parts throughout the several views.

Referring to the lettered parts of the drawings, A A are the main wheels, which are adapted to travel upon one rail of the railroad-track. These wheels serve to carry the 55 frame and are also the driving-wheels, and on account of their double function I call them "carrying" and "driving" wheels. These wheels carry the frame of the machine, which consists of a hollow tube B, having 60 cross-arms C, which are bent down over each side of the wheels. These arms C are connected to plates D at the corners of the frame which receive the axles of the wheels A. Suitable adjustment of the axle is afforded 65 in the slots at the center of the plates. The plates are connected together at each side, so that the frame is strengthened by the tubes C' C'. In the front end of the top tube B is the tube B', which carries the cross piece 70 or arm B'', to the ends of which the operating-levers F F are pivoted independently at each side. The tube B' is adjustable in the top tube B and is locked adjustably in its position by the pin e, inserted through holes 75 in both of them.

On the axle of each wheel A, to each side of the same, is a small sprocket-wheel or pinion A', referred to in the claims as "actuating-wheels." Connecting these pinions together 80 on each side are sprocket-chains E, which are preferably formed with ratchet-teeth on the outside thereof.

Surrounding each chain is a section of tube I, carrying a pawl c, held in engagement with 85 the ratchet-teeth d d by the spring r. Connected to each of these tubular sections are arms E', which extend forward and are pivotally connected to the lower ends of the operating-levers F F. Foot-rests a a are secured 90 to the bottom of each lever F F and hand-rests a' a' at or near the top.

Secured to the top of the frame is the usual seat G, with a tool-box or other receptacle or possibly a secondary seat G' to the rear. 95

Extending from the forward part of the main frame of the machine, pivotally connected thereto, is an arm H, carrying a guide-wheel J, adapted to fit upon the opposite rail of the track. The axle of this wheel is telescoped to the arm H, so that it can be pushed together or drawn out, as required. The 100

- brace H' is detachably connected to the arm H and pivoted to the rear of the frame to hold the arm H in operative connection. When it is desired to transport the machine, the arm 5 H' is disconnected from the arm H and both are folded along the side of the main machine, as indicated by the dotted lines in Fig. 2, and secured thereto by suitable means.
- I show no brake on my velocipede, for my 10 invention does not relate thereto, but any suitable brake can be applied.
- Having thus described in detail all of the parts of my improved railroad-velocipede, I 15 will now briefly state its operation.
- 15 The operator takes his position on the seat G and places a foot on each rest a a and adjusts the tube B', so that the handles a' a' at the top of the levers F are in convenient reach. Then the levers are moved either alternately or together and for any distance required and act upon the chain through the pawl c at each side. By moving the levers a full stroke the driving-wheels will be revolved several times, propelling the velocipede very 25 rapidly, and by shortening the stroke short impulses only are given. Thus it is clear that any length of stroke drives the machine, and levers F can be operated alternately and they can be operated by the hands alone or the 30 feet alone, permitting such a variety of movements to the operator that the work is not fatiguing. By alternating the movements of the levers continuous power is applied, which assists greatly in climbing grades.
- 35 Having thus described my improved railroad-velocipede, I desire to state that I am aware that it is capable of great variations in the details without departing from my invention.
- 40 The parts of the frame need not necessarily be tubular. That is the preferred construction. The fulcrum of the lever need not necessarily be adjustable, though it is very convenient and possesses great merit.
- 45 In Fig. 7 I show a modification of the pawl C, which is adapted to engage between the links of the chain. I am aware that the same device might be constructed to take hold of any kind of driving chain or belt and do not 50 wish to be confined in my claims to the particular structure here shown. I am aware also that the movement I have here shown is applicable to other purposes than that of propelling velocipedes or bicycles and, in fact, 55 that it is adapted to use in a great variety of machines so far as the propelling mechanism is concerned. This propelling means is adaptable to almost any kind of foot-power machinery—such as lathes, scroll-saws, jigsaws, polishers, and for similar purposes. I 60 desire to state in this connection that by a little adaptation of the construction a belt and friction-pulley might be utilized in place of the sprocket-chain and sprocket-gears, though 65 the sprocket-gears are much preferred by me. It will be observed that, broadly considered,

a sprocket-chain and belt are mechanical equivalents. I am also aware that it is adaptable for use upon hand-bellows—in fact, wherever any similar power may be utilized. 70

Having thus described my invention, what I claim as new, and desire to secure by Letters Patent, is—

1. In a railroad-velocipede the combination of a suitable frame made up of top tube B, 75 and cross-pieces C, C, and side pieces C', C', secured together at each corner by the plates D, D, D, D; driving-wheels A, with suitable sprocket-pinions to each side thereof carried between the plates D, at each end; the 80 sprocket-chains E, on each side of the wheels connecting the pinions A', together; a bar B', telescoping onto the top bar B, at the top of the frame carrying a cross-piece B''; propelling-levers F, F, with the handles a', a', at 85 the top pivoted on each side of the cross-piece B''; sections of tube I, on each driving-chain with pawls c thereon having springs r, for retaining them in position; connections E', E', connecting the levers F, F, and the tubes I, 90 together at each side of the machine for propelling the same and a suitable arm with the guide-wheel for the opposite rail of the track as specified.

2. In a railroad-velocipede the combination 95 of a suitable frame; carrying and driving wheels to the front and rear thereof adapted to ride on one rail of the track; sprocket-wheels on the axles of said carrying-wheels to each side thereof; sprocket-chains coupling the wheels on each side; a ratchet means suitably guided on each of said chains; a lever on each side of said frame; connections from each lever to the ratchets; hand and foot rests on the levers as specified, and an 105 arm with a guide-wheel thereon for the opposite rail of the track as specified for the purpose specified.

3. In a railroad-velocipede the combination 110 of a suitable frame; carrying and driving wheels to the front and rear thereof adapted to ride on one rail of the track; sprocket-wheels on the axles of said carrying-wheels to each side thereof; sprocket-chains coupling the wheels on each side; a ratchet means 115 suitably guided on each of said chains; a lever on each side of said frame; connections from each lever to the ratchets, for the purpose specified.

4. In a railroad-velocipede the combination 120 of a frame: suitable wheels to carry and propel the same; a pair of actuating-wheels and suitable connections between the same as a chain or equivalent; a ratchet means to engage said connection and a suitable lever with connection to said ratchet means for the purpose specified.

5. In a railroad-velocipede the combination 130 of the frame; suitable wheels to carry and propel the same a pair of actuating-wheels; a suitable connection between the same as a chain or equivalent; a ratchet means to en-

gage said connection; and a suitable means of reciprocating said ratchet means; for the purpose specified.

6. In a railroad-velocipede the combination of a suitable frame; carrying and driving wheels under the same; a pair of independent operating-levers with hand and foot rests thereon; and independent connections from each lever to the driving-wheels comprising ratchet devices for the purpose specified.

7. In a velocipede, the combination of a suitable frame; driving and carrying wheels under the same; a sprocket-chain connected by suitable gears to a driving-wheel; a tubular slide carried, guided and supported by said

chain; a ratchet-pawl on said slide to engage the chain; and a lever connected to said slide to reciprocate the same as specified.

8. In a propelling mechanism the combination of suitable sprocket-wheels, a sprocket-chain connecting the two with ratchet-teeth formed on the links thereof; a slide with a ratchet-pawl to engage the same and suitable connections to reciprocate the slide.

In witness whereof I have hereunto set my hand and seal in the presence of two witnesses.

GEORGE ELMER HEATON. [L.S.]
